US00D630093S

(12) **United States Design Patent**
Bardet

(10) **Patent No.:** **US D630,093 S**
(45) **Date of Patent:** **** Jan. 4, 2011**

(54) **CLOSURE**

(75) Inventor: **Philippe Bardet, Gleize (FR)**

(73) Assignee: **Obrist Closures Switzerland GmbH, Reinach (CH)**

(**) Term: **14 Years**

(21) Appl. No.: **29/363,583**

(22) Filed: **Jun. 11, 2010**

(51) LOC (9) Cl. **09-07**

(52) U.S. Cl. **D9/438; D9/447; D9/453; D9/448**

(58) **Field of Classification Search** **D9/724, D9/454, 453, 449, 448, 447, 435, 434, 418; D28/7; D24/129, 115; 604/414, 411, 403; 422/103; 239/327; 222/522, 211, 209, 109; 221/63; 220/254.1-254.4; 215/247; 206/824; 141/329**

See application file for complete search history.

(57) **CLAIM**

The ornamental design for a closure, as shown and described.

DESCRIPTION

FIG. 1 is a front perspective view of the invention.

FIG. 2 is a top plan view of FIG. 1.

FIG. 3 is a right side elevation view of FIG. 1.

FIG. 4 is a front elevation view of FIG. 1.

FIG. 5 is a left side elevation view of FIG. 1; and,

FIG. 6 is a rear perspective view of FIG. 1.

The invention is shown mounted on a surface and contains no claim to a bottom view which contains no ornamental design feature. The broken lines in the drawing depict environmental subject matter only and form no part of the claimed design.

1 Claim, 6 Drawing Sheets
